Primary Examiner — Robert M. Spear(74) *Attorney, Agent, or Firm* — Syncoda LLC; Feng Ma(57) **CLAIM**

The ornamental design for a printer, as shown and described.

DESCRIPTION

1. Printer

1.1 : Front

1.2 : Back

1.3 : Left

1.4 : Right

1.5 : Top

1.6 : Bottom

1.7 : Perspective

1.8 : Front view of a second state

1.9 : Back view of a second state

1.10 : Left view of a second state

1.11 : Right view of a second state

1.12 : Top view of a second state

1.13 : Bottom view of a second state

1.14 : Perspective view of a second state

1.15 : Perspective view of a third state

Figs. 1.8-1.14 represent a second configuration with the input tray in an open position; fig. 1.15 represents a third configuration with input tray and pen door in an open position.

1 Claim, 15 Drawing Sheets(56)
